CONTROL SWITCH

John Struthers Dunn, Mount Airy, Philadelphia,
Pa., assignor to Struthers Dunn Inc., Philadelphia, Pa., a corporation of Pennsylvania

Application March 10, 1936, Serial No. 68,039

4 Claims. (Cl. 200—67)

My invention relates to electrical control switches, particularly of that type effecting circuit rupture or closure by snap action.

In accordance with my invention there is associated with a toggle, or equivalent structure effecting snap action, a movable frame or equivalent structure to which, and not to the toggle, is applied through the contacts themselves the force which actuates or controls the toggle or equivalent structure.

Further in accordance with my invention the frame or equivalent structure may comprise pivoted elements pivotally tied to each other to insure their movement in unison; or may comprise elements secured in substantially fixed relation to each other and pivoted as a unit; more particularly, elements or sides of the frame or unit are disposed on opposite sides of and preferably extend substantially parallel to one of the movable elements of the toggle or equivalent structure; and there are provided stops, for limiting the frame travel in either direction, which preferably are non-yielding or rigid and so serve, due to the impacts of the frame thereon, to deliver hammer blows thereto for insuring good "makes" and "breaks" at and between the frame contacts and the contact carried by the toggle or equivalent snap-action member.

Further in accordance with my invention there coacts with the frame in its actuation or control, springs, the tension or compression of one of which is changed upon application of the primary actuating or control force, representative of or responsive to pressure, temperature or other varying magnitude or condition, to permit another of the springs to gain control of and actuate the frame in one direction, and upon subsidence of the primary force the frame is actuated in reverse sense; more particularly there coacts with the frame a member or rod with which one or more of the aforesaid springs coacts in the control or actuation of the frame, and preferably force is applied to the frame by or through the rod in one sense or direction only; and more particularly there are provided means, preferably adjustable upon or with respect to the aforesaid rod or member, for varying or changing the coaction of the aforesaid springs or equivalent means to determine at what magnitude of the primary actuating force the frame shall be actuated or controlled.

My invention resides in the features of construction and combination hereinafter described and claimed.

55 For an illustration of some of the various forms

my invention may take, reference is to be had to the accompanying drawing, in which:

Figure 1 is a plan view, partly in section, of a control switch embodying my invention;

Fig. 2 is a plan view, partly in section, of a modified form of my invention.

Referring to Fig. 1, within a housing there is secured a block 2, of insulating material when the housing is of metal, in which there is a pivot recess 3 in which is pivoted at its one end the longer arm or link 4 of a toggle. At its upper end the toggle element 4, in this instance of metal, is pointed or has a knife edge 5 engaging in a pivot recess or V-notch 6 at the lower end of the second toggle arm or element 7 which at its upper end has a pivotal point or knife edge 8 engaging in the pivot recess or V-notch 9 in a plunger 10, passing freely through the wall of housing 1, thrust downwardly by spring 11 confined between the plunger 10 and the inner end of the screw 12 threadably adjustable in the sleeve 13 carried by the housing 1.

In the position illustrated in Fig. 1 the toggle 4, 7 is in one of its extreme or "broken" positions; its dead-center position, immediately to either side of which a snap action begins, corresponds with the circumstances that the pivots at 3, 5 and 8 are all simultaneously upon an imaginary straight line, or when the pivot 5 lies on the imaginary straight line extending from pivot 3 to pivot 8.

Disposed on opposite sides of and preferably, as shown, parallel to and enclosing or embracing the toggle element 4 are the frame elements 14 and 15, in this instance of metal, pivoted respectively at 16 and 17 in upstanding portions of the metal brackets 18 and 19 secured to the block 2.

Secured to and in conductive relation with the toggle element 4 is the switch contact 20 adapted to coact with the contacts 21 and 22 secured to and conductively connected with the frame elements 15 and 14, respectively.

To cause the frame members 14 and 15 always to move in unison with each other, they are mechanically tied together by the member 23, of insulating material, pivoted to those members at 24 and 25.

Conductors 26, 27 and 28, of the circuits to be opened and closed, connect respectively with the toggle element 4, and the aforesaid brackets 18 and 19, whereby the conductors 26, 27 and 28 are in electrical communication with the contacts 20, 21 and 22, respectively.

Screws 29 and 30, threaded through the opposite walls of housing 10, have at their inner ends

heads or stops 29a and 30a for limiting the travel in either direction of the frame 14, 15 and of the toggle member 4. The screws 29 and 30 may be provided at their outer ends with screw-driver slots for effecting their adjustments to desired positions, in which they may be held by lock nuts 29b and 30b.

The stops 29a and 30a, preferably rigid or non-yielding, deliver to the frame elements 14 and 15, due to their impact upon the stops 29a and 30a, hammer blows or jars which are communicated to the opposite frame element through the tie member 23. Such a hammer blow contributes to a good "make" at and between the toggle contact 20 and either of the frame contacts 21, 22; and the hammer blow contributes also to a good "break" between the contact 20 and either of the frame contacts 21, 22. Should the contact 20, in the circuit-closing position illustrated, adhere to the frame contact 22, due to mechanical sticking or from slight electrical fusing of the contacts to each other, upon actuation of the frame to cause the frame member 15 to impact against the stop 30a, the jar or hammer blow so imparted to the frame element 15 is communicated through the frame member 14 to contact 22 to break it loose from the contact 20 which then snaps across into engagement with contact 21.

The circuit through conductors 26 and 28, shown as closed by virtue of engagement of contacts 20 and 22, may be opened by applying force to the frame 14, 15 to cause the upper end of the frame to move towards the left about the pivots 16 and 17. In consequence pressure is exerted upon the toggle contact 20 through the frame contact 22, so in engagement with and pushing upon the contact 20 causes them to move together, maintaining stable, non-chattering good contact, until the toggle member 4 reaches and slightly passes dead-center position, whereupon member 4 and its contact 20 snap toward the left, making a quick break as between contacts 22 and 20, the latter then coming into engagement with contact 21 on frame element 15, the parts coming to rest with the frame member 15 against stop 30a and frame member 14 separated from stop 29a. During switch operation one of the frame contacts exerts pressure upon contact 20 at their engaging faces as effected by application of actuation or control of the frame as hereinafter described.

To open circuit at the contacts 20 and 21 and to reclose it at 20, 22, force is applied in reverse sense to the frame 15, 14, causing action like, but the reverse of, that above described, terminating when the frame member 14 again engages its stop 29a.

Structure of this type and mode of operation is characterized by the fact that the contact movable with snap action does not coact with a stationary contact; on the contrary the frame contact, which coacts with the contact of the toggle (or equivalent structure effecting snap action), itself moves, exerts pressure upon the toggle contact, and follows it with continuance of the pressure until inception of the snap action, whereupon the toggle contact quickly separates from the pressure-applying contact, rupturing the circuit with a quick, clean and sharply defined break.

During such application of force to the toggle or equivalent snap-action element and while at rest the coacting contacts maintain good and stable electrical contact with each other; they do not chatter on or with respect to each other,

as might otherwise occur due to vibrations within the switch structure or imparted thereto by forcible or heavy external vibrations, and so avoid substantial variations in resistance at the contacting faces, and so especially avoid small or minute circuit ruptures. The avoidance of chatter prevents damage to the contacts themselves, and eliminates effects interfering with radio reception.

A further advantage resides in the wiping action upon each other of the coacting contacts at their contacting faces while they move in engagement with each other until inception of the snap action. During their movement, they rub upon each other in the plane or surface of contact, by virtue of the fact the toggle element or equivalent and the frame or frame element are not pivoted about the same axis; and the wiping or rubbing action maintains the contact faces clean.

Generally the frame 14, 15 is actuated or controlled by application of force representative of or responsive to change in temperature, pressure or other condition or circumstance.

Reverting to Fig. 1, there extends freely through frame elements 14 and 15 and toggle element 4, a rod 31 surrounded by the helical spring 32 confined under compression between the frame element 15 and a collar or head 33 whose hub 33a is secured, as by a pin, on rod 31; there may be provided a disc 32a upon 33 for centering the spring 32.

Threaded on rod 31, for adjustment thereon, is a member or nut 34 which through the insulation 34a abuts against the rounded or more or less knife-edge abutment 35 on frame member 14. Adjustment of nut 34 upon rod 31 varies or adjusts the effect of the spring 32, and so adjusts the point of response or actuation of the switch as affected by force exerted upon rod 31 in accord with temperature, pressure or some other condition or circumstance.

Generically to illustrate means for exerting upon the rod 31 a force in accord with pressure, temperature or other condition, there is shown a thermo-responsive device comprising a tube 36 containing a suitable fluid which, in response to changes in temperature to which tube 36 is subjected, exerts corresponding fluid pressure upon the corrugated metal sylphon or bellows 37, and its end or head 38, spaced from the walls of chamber 39 with which tube 36 connects. The chamber 39 is secured by screws 39a to housing 1. At the end of chamber 39 is a plate 40 closing the space within chamber 39 between it and the sylphon 37. The fluid pressure exerted or applied causes head 38 to exert a force toward the right.

The member or rod 31 extends through the wall of the housing 1 for movement to the right or left. At its left end the rod 31 is provided with a head 41 between which and the housing wall is confined under compression a helical spring 42 adapted to thrust against the head 41 tending to move the rod 31 toward the left. The head 41 abuts against the head 38 of the sylphon 37 or bellows 37 or, in any event, is so related to the head 38 that when fluid pressure exerted upon the sylphon increases, the head 38 forces the head 41 toward the right, compressing or increasing the compression of the spring 42 so as to allow the spring 32 to gain control of and actuate the frame 14, 15 in one direction to cause actuation of the switch elements. Upon decrease or subsidence of the fluid pressure the spring 42 expands and forces the rod 31 again

toward the left, overcoming spring 32, and causing actuation of the frame in opposite direction, correspondingly to actuate the switch in opposite sense.

5 The springs 42 and 32 are so related, and their relative tensions or compressions are such, that increase of fluid pressure upon the sylphon 37 causes compression or further compression of the spring 32 to cause actuation of the switching mechanism in one sense, and upon subsidence or decrease in the fluid pressure the net force applied to the frame causes actuation of the switch in opposite direction. The adjusting nut or member 34 serves to adjust the relation to each other of the tensions or compressions of the springs 32 and 42, and so in effect determine at what temperature or other magnitude of a condition or quantity the frame should be actuated in either direction.

20 While there are shown two contacts, 21 and 22, coacting with the movable contact 20, it shall be understood that if only one circuit is to be controlled, one or the other of the contacts 21, 22 may serve merely as a button or member for pressing against the contact 20, and in such case one or the other of the conductors 27 or 28 would not be employed. In this connection, it shall be further understood structure of the character and mode of operation described may be utilized 25 for controlling more than the two circuits which have been illustrated by way of example.

Any of the circuits controlled by the width of the character described may include any desired translating device, such as an electric lamp, or lamps, an electric motor, a heating resistance or any other electrical impedance, an electromagnet, a relay winding, or any other controlled or controlling device.

In Fig. 2 there is shown a modification, again 40 illustrated, by way of example, as actuated or controlled by a thermo-responsive device such as illustrated in connection with Fig. 1.

In Fig. 2, 43 is a base or plate of insulating material having marginal upstanding integral 45 members 43a over which may fit a cover member, not shown, enclosing the entire mechanism except the thermo-responsive or other primary force-applying means, and excepting also the adjusting member hereinafter referred to.

50 In this instance again the frame encloses or embraces the toggle structure or equivalent snap action device.

The longer toggle element or member 44, of 55 metal, is provided with a pivot 45 which at its inner end is received in a pivot-bushing carried by the base 43, and which at its outer end is received in a pivot bushing carried by a plate, not shown, adapted to be secured by screws at 46, 46 to the upstanding lugs 47, 47 molded integral 60 with the base 43. These lugs are provided with pins 48, 48 registering in holes in the plate nicely to determine the location of the pivotal axis of the toggle member 44.

65 Adjacent its other end the toggle element 44 carries a tubular member 49 in which is longitudinally movable the piston 50 between whose lower end and the lower end of the member 49, within the latter, is confined a spring 51 under compression. The complementary toggle element 70 52, illustrated as a metal disc having a peripheral knife edge, pivots in a recess in the upper end of the plunger 50 and also in a pivot recess in the metal post 53 fixed to the base or plate member 43.

75 The toggle structure described is of the gen-

eral construction and mode of operation of that described in connection with Fig. 1, producing a snap action as the member 44, through the contacts, is forced to right or left by the frame. Upon the member 44 is secured the contact 20a 5 which, like contact 20 of Fig. 1, comprises portions or elements disposed on opposite sides of member 44 for coaction with the frame contacts 21a and 22a mounted, respectively, on screws 21b and 22b threaded through the metal sides 55, 10 56 of the frame and held in adjusted position by the lock nuts 21c and 22c, respectively. The contact 20a is connected to the binding post 54 through conductor 26a, and thence by a continuing conductor, not shown, connected to the 15 binding post 54 to the external circuit. The conductor 26a connects to a clip 26b, at a point thereof adjacent the pivot 45, and the clip is itself secured to the member 44 by screw 26c.

The frame comprises the aforesaid arms or side 20 elements 55, 56, disposed on opposite sides of the toggle, and so enclosing or embracing it. At their upper ends the frame elements 55, 56 are rigidly secured together by the tie member 23a of insulating material; at their lower ends they 25 are secured by screws 57, 57 to the lugs 58, 58 integral with the frame block 59 of molded insulating material. The block 59, side elements 55, 56 and tie member 23a constitute a unit, movable as such about the pivot 60 carried by 30 the downward extension of the block 59 and bearing at its inner end in a pivot bushing carried by the base 43 and at its outer end in a pivot bushing carried by a plate, not shown, adapted to be held by screws 61, 61 threaded into the up- 35 standing lugs 62, 62 of insulating material molded integral with the member 43. In the lugs 62, 62 are disposed pins 63, 63 for nicely determining the position of the plate and therefore the pivot 60.

To the binding posts 64 and 65 may be attached the external circuit conductors, not shown, which then communicate through the binding posts and the conductors 66, 67 with the conductor clips 66a and 67a which are held by 45 aforesaid screws 57, 57 against and in electric communication with the metallic frame members 55, 56 which, in turn, electrically communicate with the aforesaid contacts 21a and 22a.

Attached at its one end to the eye 68 carried 50 by the frame member 56 is the spring 69 whose other end is held by the posts 70 carried by or molded in the base 43.

The spring 69 is under tension, exerting a force upon the frame, causing it to move or tend to 55 move clockwise about its pivot 60.

When otherwise free to do so, the spring 69 moves the switch to the position illustrated, in which the upper end of the toggle member 44 has snapped to the right, bringing contact 20a 60 into engagement with contact 22a.

The limits of travel of the frame are determined by the screws 71, 71 threaded through the aforesaid post or lugs 47, 47. The screws are held in their adjusted positions by the lock nuts 65 71a, 71a, and the inner ends of the screws are frame stops corresponding with the stops or heads 29a and 30a of Fig. 1. The impacts of the frame members 55, 56 upon the stops 71, 71 effect the jars or hammer blows having the effects of the 70 stops 29a and 30a hereinbefore described in connection with Fig. 1.

The rod 31, generally of metal, extends loosely through the tail of frame block 59, and upon the tail of the block, to one side of pivot 60, are 75

mounted, on opposite sides of the rod 31, abutments or knife-edge blocks 72, generally of metal, against which bears the metal collar 73 on the metal bushing 74 which extends through and is 5 rotatable in a hole in the right-hand lug or block 62. The bushing 74 is threaded on the rod 31, and is rotatable by the manually operable knob 75 secured to the bushing 74 and having in its face parallel to the outer face of the right-hand block 62 an arcuate slit into which extends the end of the pin 76, carried by block 62, for limiting the rotation of the knob 75 and bushing 74 to an angle of about 360°, which extent of rotation of the bushing is generally sufficient for 10 the desired range of adjustment, which is dependent upon the pitch of the threads of the rod 31 and bushing 74.

The rod 31 at its left-hand portion is of rectangular cross-section, movable to the right and 15 left within a rectangular hole in the left-hand block 62, or in a plate held thereby, whereby the rod 31 is held against rotation.

As in the case of Fig. 1, the helical spring 42, surrounding the left end of the rod 31, is confined 20 between the head 41 on the rod and one face of the left-hand block 62 or the aforesaid plate held thereon. The spring 42 exerts a force on the rod 31 causing it to move toward the left, and that force is communicated through the aforesaid collar 73 to the knife-edge block 72 carried by the 25 frame.

When the pressure in the space about the sylphon 37, within the chamber 39, increases, the sylphon exerts a force toward the right on the 30 head 41 of the rod compressing the spring 42, so diminishing the force exerted by the collar 73 upon the knife-edge block 72 of the frame, and so permitting the spring 69 to actuate the switch to the position illustrated. Upon decrease or 35 subsidence of the pressure within the chamber 39, the spring 42 gains control, causing the collar 33 to thrust more strongly against the knife-edge block 72 of the frame and so actuate it, in opposition to spring 69, to cause the switch 40 to move to its other position, corresponding with engagement of the frame member 56 with the stop screw 71 at the left.

By rotating the knob 75, the bushing 74, to which it is secured, is adjusted to the right or 45 left upon the rod 31, so adjusting the relation to each other of springs 42 and 69 to determine at what temperature, pressure, or other magnitude of the condition the switch shall be controlled or actuated, and particularly at which it shall be 50 actuated to the position illustrated, under the then predominating influence of spring 69.

As in the case of Fig. 1, the force applied to 55 the snap action or toggle structure is transmitted through the contacts, which are non-chattering and wipe upon each other.

The toggle elements 4 and 44 are preferably rigid or insubstantially flexible, and the frame members 14, 15 and 55, 56 are preferably rigid, though they may be to substantial extent yielding or flexible. In the examples illustrated, all 60 the aforesaid toggle and frame parts are rigid or substantially inflexible, though they may be otherwise when circumstances require or permit.

In apparatus of the character herein described 65 the snap action of the switch will take place at a predetermined pressure, temperature, or the like, to effect circuit control in one sense, and at a somewhat different pressure, temperature or the like to effect control in opposite sense; which 70 is to say, that there is a difference or differential

between the pressures, temperatures or the like at which the snap action occurs in its respective directions of operation.

Under differing conditions and circumstances such differential may be necessarily or desirably 5 greater or less. To adjust or vary such differential, various adjustments may be made in the apparatus shown.

The extent or magnitude of the differential may be adjusted by adjusting the amount or 10 extent of lost motion between suitable or certain parts of the structures. For example, in Fig. 1 either or both of the stops or abutments 29a and 30a may be adjusted inwardly or outwardly to allow and procure the desired extent or amount 15 of lost motion, and so adjust the magnitude of the differential; and in Fig. 2 the adjustment of the magnitude of the differential may be effected by adjusting inwardly or outwardly either or both of the abutments or stops 71. In both cases such 20 adjustments of the stops or abutments, or either of them, adjust the amount of permissible pivotal motion of the frame members 14 and 15, Fig. 1, and the frame, Fig. 2, whose side elements are 25 55 and 56.

Furthermore, adjustment of lost motion, which determines the magnitude of the differential, may also be adjusted in Fig. 2 by adjusting either or both of the contacts 21a and 22a toward or away 30 from each other.

In both Figs. 1 and 2, the extent of lost motion may be varied, and so variably determine the differential, by effecting variable lost motion between either end of spring 42 and its corresponding abutment.

In general, the greater the lost motion, procured in any of the manners aforesaid or equivalents thereto, the greater will be the differential.

What I claim is:

1. A snap action switch comprising a member 40 adapted to snap to positions on opposite sides of dead-center, a pivoted frame comprising members disposed on opposite sides of said first-named member, a contact carried by said first-named member, contact structure coacting with said contact and carried by said frame, a spring exerting a force on said frame to actuate it and thereby to actuate said first-named member through said contact and said contact structure, a second spring opposing and of less strength than said 45 first-named spring for actuating said frame in opposite direction, means for overcoming the force of said first-named spring to produce operation of said frame by said second spring, and means for controlling the relative magnitudes of the 50 forces exerted on said frame by said springs.

2. A snap action switch comprising an elongated member pivoted at one end, and means connected to its opposite end for operating said member with a snap action to positions on opposite 55 sides of dead-center, a pivoted frame comprising members disposed on opposite sides of and extending lengthwise of said first-named member generally parallel thereto, a contact carried by said first-named member adjacent said operating 60 means, contact structure coacting with said contact and carried by said frame, a spring exerting on said frame at a point spaced from its pivotal axis, a force to actuate it and thereby to actuate said first-named member through said 65 contact and said contact structure, a second spring opposing and of greater strength than said first-named spring, means for exerting a force on said second spring to permit said first-named spring to actuate said frame, and means 70 75

for varying the relative magnitudes of the forces exerted upon said frame by said springs.

3. A snap action switch comprising a member adapted to snap to positions on opposite sides of dead-center, a pivoted frame comprising members disposed on opposite sides of said member, coacting contacts carried by said member and said frame, a spring for actuating said frame in one direction, a rod extending free of said frame from one side to the opposite side thereof, an abutment of restricted contact area on said frame, a coacting abutting member on said rod, a spring opposing and of greater strength than said first-named spring and exerting a force on said frame through said abutment and abutting member, and means for applying to said rod a force in opposition to said second-named spring.

4. A snap action switch comprising a member

adapted to snap to positions on opposite sides of dead-center, a unitary frame comprising members disposed on opposite sides of said first-named member, contacts carried by said first-named member and said frame, a pivot for said unitary frame, a rod extending loosely through a portion of said frame, a member on said rod abutting against one side of said frame, a spring on the opposite side of said frame from said abutting member for transmitting therethrough to said frame a control force, a second spring for actuating said frame in one direction and overcome by said first-named spring for actuating said frame in opposite direction, and means for exerting on said first-named spring a force overcoming said control force to produce actuation of said frame by said second-named spring.
